DAVID B. COX, OF TROY, NEW YORK.

Letters Patent No. 79,108, dated June 23, 1868.

IMPROVEMENT IN EXTENSION-RING FOR BASE OF COOKING-STOVES.

The Schedule referred to in these Letters Patent and making part of the same.

TO ALL WHOM IT MAY CONCERN:

Be it known that I, DAVID B. Cox, of Troy, in the county of Rensselaer, and State of New York, have invented an Improvement in Heating-Stoves; and I do hereby declare that the following is a full and exact description thereof, reference being had to the accompanying drawings, making part of this specification—

Figure 1 being a top view of the extension-ring in which my improvement consists.

Figure 2, a central vertical section representing the principal parts of a stove, with the extension-ring applied thereto.

Figure 3, a view of a stove provided with the extension-ring applied thereto.

Like letters designate corresponding parts in all of the figures.

My invention consists in an extension-ring, A, to rest upon the base, B, of a stove, and to receive upon it the body or upper part C of the stove, being removable and replaceable at pleasure, in order to adapt stove-bodies of different sizes to one base, or to bases of one size, substantially as herein specified.

The mode by which the extension-ring effects the purpose is illustrated in fig. 2. Let *a* represent the flange at the upper edge of the base, on which the body of the stove ordinarily fits. Then if it is desired to attach a body, C, of larger size to the same, or same-sized base B, the extension-ring A is placed upon the base, and as the flange *b* of the ring is of larger diameter than the flange *a* of the base, it will receive a larger body, C, as desired. Extension-rings of different sizes for one base may be used, to receive as many additional sizes of stove-bodies; and a ring may be applied in the same way, to diminish instead of increasing the size of the stove-body.

The ring is made of cast iron, and may have any desired form and ornamentation.

What I claim as my invention and desire to secure by Letters Patent, is—

An extension-ring, A, applied between the base, B, and body C of a stove, substantially as and for the purpose herein specified.

The above specification of my improvement in stoves signed by me, this twenty-sixth day of March, 1868.

DAVID B. COX.
